Specification of Letters Patent.

Patented Feb. 7, 1922.

Application filed November 6, 1920. Serial No. 422,271.

To all whom it may concern:

Be it known that I, IVAR CARLSON, a citizen of Sweden, residing at Leominster, in the county of Worcester and State of Massachusetts, have invented a new and useful Improvement in Aeroplanes, of which the following is a specification.

My invention has reference to an improvement in aeroplanes and more particularly to an improvement in the aeroplane shown in my application for a United States patent filed October 27, 1919, Serial No. 333,559, allowed August 3, 1920.

The object of my invention is to improve the construction and operation of such an aeroplane whereby the actions of rising and descending vertically and of flying are greatly facilitated.

My invention consists in the peculiar and novel construction and improvements in such an aeroplane, said new construction and improvements being principally in the planes, top, front and rear rudders and in the means for operating the same, as will be more fully set forth hereinafter and claimed.

Figure 1 is a top plan view of my improved aeroplane showing the movable side planes in the raised position for flying.

Figure 2 is a vertical longitudinal sectional view through the aeroplane taken on line 2, 2 of Figure 1, and

Figure 3 is a front view of the aeroplane showing the movable side planes in the lowered position, in broken lines, for rising or descending vertically and in the raised position in full lines for flight.

In the drawings 4 indicates the fuselage, 5 the central plane, 6, 6 the side planes, 7 the top rudder, 8 the front rudder, 9 the twin rear rudder, 10 the engine, 11 the tractor shaft on which is a tractor helix 12, 13 the propeller shaft on which is a propeller helix 14 and 15 the transmission of my improved aeroplane.

45 The fuselage 4 consists of a suitable frame 16 as shown, supporting the engine 10, wheels 17, 17, tractor bearing 18, propeller bearing 19, central plane 5, side planes 6, 6, transmission 15 and operator's seat 20 and the frame terminates in a front overhanging end 21 and a rear overhanging end 22.

The central plane 5 is tent shaped in cross section. It extends the length of the fuselage 4 and the slopes 23, 23 of the plane

form on the underside of the plane an inverted flattened V shape trough 24 which extends the length of the plane. This central plane 5 is rigidly secured to the frame 16.

The side planes 6, 6 are each in the form 60 of a flat rectangular shaped plane. They extend the length of the central plane 5 on each side and are hinged at their inner edges at 25, 25, to the frame 16, as shown in Figure 3 and form a continuation of the central 65 plane 5. The width of these side planes is such that when in the lowered position for rising or descending the outer edges of the planes come at approximately the center of the wheels 17, 17. The side planes are 70 operated by a hand lever 26 to raise or lower the side planes. This hand lever 26 is pivotally secured to the frame 16 in a convenient position to the operator's seat 20, as shown in Figure 2. From this hand lever 75 26 rods 27, 27 extend to pivot connections 28, 28, on the side planes 6, 6, as shown in Figure 3.

The top vertical rudder 7 is flat and elongated in form, it is pivotally secured adjacent 80 its forward end to the frame 16, at 29 on top of the central plane 5 and extends centrally lengthwise of the central plane. It is operated to steer the aeroplane sidewise by wires 30, 30 which are secured at one end 85 to each side of the top rudder 7. Each wire 30, 30 extends down over pulleys 31, 31 and then to a foot treadle 32 on the frame 16 in a convenient position for the foot of the operator, as shown in Figures 2 and 3. 90

The front rudder 8 is flat and semi-circular in form. It is pivotally secured at 33 in a horizontal position, to the end of the front overhanging end 21 of the frame 16. It is operated to steer the aeroplane up or down 95 by wires 34, 34, which are secured at one end to the rudder and at their other ends to a hand lever 35 pivotally secured to the frame 16 in a convenient position to the operator's seat 20, as shown in Figure 2. 100

The twin rear rudder 9 consists of a horizontal rudder 36 and a vertical rudder 37. The horizontal rudder 36 is the same as the front rudder 8, it is pivotally secured at 38 to the end of the overhanging end 22 of the 105 frame 16. It is operated to steer the aeroplane up or down by wires 39, 39 which are secured at one end to the horizontal rudder

36 and at their other ends to a hand lever 40, pivotally secured to the frame 16 in a convenient position to the operator's seat 20. The vertical rudder 37 is pivotally secured 5 at 41 to the horizontal rudder 36 and it has a slot 42 through which the horizontal rudder 36 extends, whereby the horizontal and vertical rudders have independent movements. The vertical rudder 37 is operated 10 to steer the aeroplane sidewise by wires 43, 43 which are secured at one end to the vertical rudder 37. These wires 43, 43 extend over pulleys 44, 44 and then downwards to a foot treadle 45 to which they are secured, 15 the foot treadle 45 being in a convenient position to the operator's seat 20, as shown in Figure 2.

The engine 10 is secured to the frame 16, it may be of any well known form of a gas 20 engine supplied with fuel by a pipe 46 from an overhead fuel tank 47. The engine is operated in the usual way not shown from the operator's seat 20.

The transmission 15 is operatively connected to a power shaft 48 which is operatively connected to the engine 10. On the forward end of the power shaft 48 is secured a bevel gear 49 meshing with a bevel gear 50 on an inclined shaft 51 rotatably 25 supported in bearings 52, 52 on the frame 16. On the forward end of the shaft 51 is a bevel gear 53 meshing with a bevel gear 54 on the tractor shaft 11, thereby transmitting power from the engine 10 to the tractor 30 shaft 11.

The tractor shaft 11 is rotatably supported in the tractor shaft bearing 18 and has fixed on its forward end the tractor helix 12 and the tractor shaft revolves preferably to the 40 right.

On the rear end of the power shaft 48 is secured a bevel gear 55 meshing with a bevel gear 56 on a vertical shaft 57 rotatably supported in bearings 58, 58 on the frame 16. 45 On the upper end of the vertical shaft 57 is a bevel gear 59 meshing with a bevel gear 60 on the propeller shaft 13, rotatably supported in the propeller shaft bearing 19, thereby transmitting power from the engine 50 10 to the propeller shaft 13.

The transmission 15, on the power shaft 48, is operated to control the same by a hand lever 61 adjacent the operator's seat 20 as shown in Figure 2. The construction of the 55 transmission, not shown, is such that through the operation of the hand lever 61 the tractor helix 12 and the propeller helix 14 may be made to revolve simultaneously to the right to propel the aeroplane in a forward 60 direction, or the tractor helix 12 may be made to revolve simultaneously to the right and the propeller helix 14 simultaneously to the left to raise the aeroplane vertically upwards. The operations of the tractor and 65 propeller helixes are the same as in my pre-

vious patent application and any form of a transmission may be used, that will accomplish the same result.

As shown in Figure 3 the central plane 5 is concaved in cross section and forms a flattened V shaped trough 24 on its under side and which extends the length of the central plane. The aeroplane when moving forward in the air moves in the direction of the arrow 62, as shown in Figure 2 and when 75 moving vertically upwards in the direction of the arrows 63, 63 as shown in Figures 2 and 3.

When in use and it is desired to arise vertically upwards, the operator seats himself 80 in the operator's seat 20 and then operates the transmission 15 by the hand lever 61, so that the tractor helix 12 will revolve to the right to move the aeroplane forward, and the propeller helix 14 to the left, to move the 85 aeroplane backwards. He then operates the hand lever 26 to close the side planes 6, 6 into position, as shown in broken lines in Figure 3. The top rudder 7, front rudder 8 and rear twin rudder 9, being in a central 90 or neutral position, as shown in full lines in the figures, the operator now starts the engine 10 in the usual way. The helixes revolving in the directions stated, cause blasts of air to meet in the center portion of the 95 trough 24 on the underside of the central plane 5 and forces the central plane 5 and with it the aeroplane vertically upwards. The air blasts now being resisted by the central plane 5 and coming together, at the central portion of the plane are forced downwards and forming an air pack against the atmosphere, also in conjunction with the first blasts of air against the plane, forces the aeroplane upwards. With the side 100

planes 6, 6 closed as shown in broken lines in Figure 3, the blasts of air are more confined to a downward direction and a better air pack is obtained, thereby increasing the upward or rising force of the aeroplane, per 105 horse power developed, in the engine. When the aeroplane has reached the desired height, the engine is reduced in speed to a point where the aeroplane ceases to rise and the aeroplane may be held stationary so as to 110 hover over any given point on the ground, or over other flying machines. When it is desired to go ahead, the transmission 15 is operated by the hand lever 61 so that the tractor and propeller helixes will both 115 revolve to the right, both helixes now revolve in the same direction and at the same speed. As the helixes are now revolving on the same plane, or center line of the aeroplane, in the same direction and at the same speed, the 120 speed of the engine may now be increased to its maximum speed. When it is desired to alight vertically on the ground or other structures, the above operations are reversed.

My present invention lies more particu- 125

larly in new construction and operation such as the central tent shaped plane 5, the movable side planes 6, 6 the top rudder 7, the twin rear rudder 9 and the frame 16.

5 Having thus described my invention I claim as new:—

1. An aeroplane having a frame, a central plane extending lengthwise of the frame and formed to have a flattened V shaped trough 10 on its underside and extending the length of the plane, said plane being secured to the frame, rectangular shaped side planes hinged to the frame and extending the length of the central plane, means for operating the side 15 planes, a top rudder pivotally secured to the frame over the central plane, means for operating the top rudder, a front horizontal rudder hinged to the frame, means for operating the front rudder, a twin rear rudder 20 comprising a horizontal rudder hinged to the frame and a vertical rudder pivoted to the horizontal rudder, means for operating the twin rear rudder, an engine supported by the frame, a tractor shaft rotatably supported in bearings in the frame and operatively connected with the engine, a tractor 25 helix on the tractor shaft at the forward end of the central plane, a propeller shaft rotatably supported in bearings, a propeller helix on the propeller shaft at the rear end of the central plane, a transmission operatively connected with the tractor and propeller shafts, and means for operating the transmission, for the purpose as described.
- 30 2. An aeroplane having a frame with

overhanging front and rear ends, a rectangular shaped central plane extending lengthwise of the frame and having a flattened V shaped trough on its underside and extending the length of the plane, said plane 40 being secured to the frame, rectangular shaped side planes hinged to the frame and extending the length of the central plane and forming a continuation of the central plane, means for operating the side planes, 45 a rectangular shaped vertical top rudder over the central plane and pivotally secured to the frame, means for operating the top rudder, a semi-circular front horizontal rudder hinged to the front overhanging end 50 of the frame, means for operating the front rudder, a twin rear rudder comprising a semi-circular horizontal rudder hinged to the rear overhanging end of the frame and a vertical rudder pivoted to the horizontal 55 rudder, said vertical rudder having a slot through which the horizontal rudder extends, means for operating the twin rear rudder, an engine supported by the frame, a tractor helix at the forward end of the central plane and operatively connected with the engine, a propeller helix at the rear end of the frame, and operatively connected with the engine, a transmission operatively connecting the engine with the tractor and propeller helixes and means for operating the transmission, for the purpose as described.

In testimony whereof, I have signed my name to this specification.

IVAR CARLSON.
